United States Patent Office

Des. 195,770
Patented July 30, 1963

195,770

CHAIR

Richard A. Isola, Royal Oak, Mich., assignor, by mesne assignments, to Steelcase, Inc., Grand Rapids, Mich.

Filed Aug. 27, 1962, Ser. No. 71,465

Term of patent 14 years

(Cl. D15—1)

FIG. 1.

FIG. 2

FIG. 3.

FIG. 4.

FIG. 1 is a perspective view of a chair, showing my new design;

FIG. 2 is a front elevational view of the chair;

FIG. 3 is a side elevational view of the chair; and

FIG. 4 is a rear elevational view of the chair.

The dominant features of my design reside in those portions shown in full lines on the drawings.

I claim:

The ornamental design for a chair, substantially as shown and described.
